UNITED STATES PATENT OFFICE.

TORGER A. BAKKETUN, OF NORTHWOOD, IOWA.

DESIGN FOR A GAME BOARD.

Application filed November 7, 1925. Serial No. 15,381. Term of patent 7 years.

To all whom it may concern:

Be it known that I, TORGER A. BAKKETUN, a citizen of the United States, residing at Northwood, in the county of Worth and State of Iowa, have invented a new, original, and ornamental Design for Game Board, of which the following is a specification, reference being had to the accompanying drawing, forming a part thereof.

I claim:—

The ornamental design for a game board substantially as shown.

In testimony, that I claim the foregoing as my own, I have hereto affixed my signature.

TORGER A. BAKKETUN.
